REFRIGERATOR CAR

Victor E. West, New Kensington, Pa., assignor to
Standard Railway Equipment Manufacturing
Company, Chicago, Ill., a corporation of Dela-
ware

Application October 21, 1938; Serial No. 236,151

7 Claims. (Cl. 62—17)

This invention relates to refrigerator cars used to transport perishable commodities at a predetermined temperature. The essential features of such a car are an insulated structure and a refrigerating means for use in warm weather or a heating means for use in cold weather.

The invention relates particularly to refrigerator cars of the overhead bunker type. Cars of this type have the refrigerant containers suspended immediately below the roof. They are often provided with drip pans below the containers to form refrigerant compartments below the roof and adjacent the side walls of the car. It is also common to provide vertical flues associated with the side walls and extending to near the floor. These flues serve as passages for the flow of refrigerated air from the refrigerant compartment to below the floor racks of the car so that it may circulate upwardly through the lading. The flues also serve to drain off melted refrigerant when a foraminous or semi-foraminous container is used or condensation from the container when liquid retaining tanks are used.

Each side wall of a refrigerator car is provided with a door through which lading is transported into the car. These doors must be large enough to allow passage of a truck therethrough and are usually about four feet wide. The refrigeration of the car is dependent upon cold air circulating downwardly through the above mentioned flues which are associated with the side walls of the car.

The refrigerating efficiency is increased by having the melted refrigerant circulate with the air to further cool the air during passage through the side wall flues and to further insulate the walls of the car.

To interrupt a flue for a distance of four feet would obviously lessen the refrigerating efficiency, particularly since the interruption would be at the doorway where more refrigeration is desirable to overcome the effect of insulation deficiencies at the door joints.

The problem of maintaining adequate refrigeration adjacent the doorway has been solved by providing flues or ducts on the doors. When the doors are closed, the ducts are aligned with the side wall flues to form a continuous passage for the air and liquid from the refrigerant compartment to the lower part of the car. In other words, the operation is as if the doors were nonexistent.

When the doors are opened, however, the passage becomes discontinuous and the liquid which was flowing through the duct in the door falls

through the doorway. The lading which is hauled through the doorway is often of a type which may be damaged by water. Furthermore, the clothing of the workers would be made moist by the cold liquid, thus creating unpleasant and hazardous working conditions in addition to the danger of having a costly lading damaged.

The amount of liquid flowing through the side wall flues is usually increased by the opening of the doors. Heat enters the car and melts more refrigerant, thus causing a greater flow of liquid. There must also be considered the fact that refrigerator cars are often loaded before they are completely pre-cooled. Pre-cooling melts refrigerant at a rapid rate with a consequent large amount of liquid flowing through the flues.

The object of this invention is to provide a means to prevent the dripping of liquid upon lading and workers which are passing through the doorway during loading or unloading of the car. It is a further object to prevent the aforesaid dripping without impairing in any way the normal flow of air and liquid through the door duct when the door is closed. The operation of the device which I claim as my invention will be completely described by referring to the drawings.

In the drawings:

Fig. 1 is a transverse section through the door of refrigerator car showing my invention. The position shown is with the door closed. 30

Fig. 2 is a fragmentary section showing the door open.

Fig. 3 is a fragmentary view showing the flashing provided to prevent liquid entering the lading compartment. 35

Fig. 4 is a section on line 4—4 of Fig. 2.

Figs. 5 and 6 show alternate constructions.

In the refrigerator car shown in Fig. 1, the usual parts are shown, such as sub-floor 2; floor 3; side sill 4; floor rack 5; side sheathing 6; side lining sheet 7; false wall 8 forming the flue 9; roof 10; ceiling 11; outer side plate 12; inner side plate 13; refrigerant container 14; drip pan 15; door 16 having a false wall 17 forming the duct 18; threshold plate 19; and insulation 20. The container 14 shown is a semi-imperforate lower part. When the brine reaches a certain level some of it spills through the apertures 21 and flows downwardly over the drip pan 15 and through the flue 9. When the door 16 is closed, as shown in Fig. 1, the liquid flows through the duct 18.

Referring to the flues shown in Fig. 4, which is a section above the door, flues 30—31 have aligned with them the ducts 18 when the door 55

16 is closed, as shown in Fig. 1. When the door is open, as in Fig. 2, any liquid flowing through the flues 30—31 will fall into the doorway and upon any lading or person passing through the doorway. The flues 32—33 are adjacent the door 16 and are, therefore, continuous to the floor of the car. The member 34 is provided to divert liquid away from the flues 30—31 to the flues 32—33 and is tapered downwardly toward the flues 32—33. A gasket 35 of a pliable material is provided on the lower edge of the member 34 to form a watertight seal with the drip pan 15.

The member 34 is attached to the upper end of an arm 36 which is pivoted to a bracket 37 secured preferably to the side wall of the car. The lower end 38 of the arm 36 is adapted to be operated by the door 16. When the door is closed, as shown in Fig. 1, the upper edge of the false wall 17 on the door 16 bears against the lower end 38 of the arm 36 and moves it inwardly, lifting the member 34 and permitting liquid to flow through the duct 18. When the door 16 is opened, as shown in Fig. 2, the pressure against the lower end 38 of the arm 36 is released and the member 34 is allowed to rest upon the drip pan 15. When the door 16 is opened, the member falls by gravity upon the drip pan 15 due to its relatively large mass and overhanging relation to the arm 36.

Fig. 3 is a view looking toward the false walls 8—17 from within the flue 9 and duct 18. It shows a flashing 45 arranged above and to the sides of the opening 46 to prevent the splashing liquid therethrough when the door 16 is closed.

In the construction shown in Figs. 1 and 2 the member 34 rests upon the drip pan 15 by reason of its own weight. It may be desirable to provide a more positive means for holding the member down. A spring would be suitable, such as the helical spring 50 shown in Fig. 5, or the torsional spring 51 shown in Fig. 6. As shown in Figs. 1 and 2, an offset portion 52 is provided on the arm 36 to bear against the false wall 8 when the door 16 is closed to keep the member 34 and arm 36 from rattling.

The device herein disclosed is intended to stop flow of water through the doorway when the door is open. The member 34 having the gasket 35 diverts the liquid to flues 32—33. When the door is closed, a mechanism is provided to space the member 34 from the drip pan 15 and allow liquid to flow through the duct 18 and provide more efficient refrigeration at the doorway.

Means to prevent liquid flowing through the doorway when the door is open is also disclosed and claimed in application Serial No. 232,741, filed by Charles D. Bonsall on October 1, 1938.

The accompanying drawings illustrate the preferred form of the invention, though it is to be understood that the invention is not limited to the exact details of construction shown and described, as it is obvious that various modifications thereof, within the scope of the claims will occur to persons skilled in the art.

I claim:

1. In a refrigerator car having spaced apart insulated walls, an insulated roof extending therebetween, a drip pan sloping downwardly toward one of said walls and spaced below said roof to provide a refrigerant compartment therebetween, a flue associated with said wall and arranged to transmit air and liquid from said compartment to the lower part of the car, a doorway through said wall and said flue and a door adapted to close the doorway in said wall, said door

having associated therewith a duct which aligns with said flue when the door is closed to form a continuous passage, the combination of a member on the upper surface of said drip pan arranged to prevent flow of liquid through said doorway when the door is open, and means by which said member is spaced from said drip pan when the door is closed to permit flow of liquid through said duct. 5

2. In a refrigerator car having spaced apart insulated walls, an insulated roof extending therebetween, a drip pan sloping downwardly toward one of said walls and spaced below said roof to provide a refrigerant compartment therebetween, a flue associated with said wall and arranged to transmit air and liquid from said compartment to the lower part of the car, a doorway through said wall and said flue and a door adapted to close the doorway in said wall, said door having associated therewith a duct which aligns with said flue when the door is closed to form a continuous passage, the combination of a member on the upper surface of said drip pan arranged to divert liquid to the flue on either side of the doorway when the door is open, 25 and means by which said member is spaced from said drip pan when the door is closed to permit flow of liquid through said duct.

3. In a refrigerator car having spaced apart insulated walls, an insulated roof extending therebetween, a drip pan sloping downwardly toward one of said walls and spaced below said roof to provide a refrigerant compartment therebetween, a flue associated with said wall and arranged to transmit air and liquid from said compartment to the lower part of the car, a doorway through said wall and said flue and a door adapted to close the doorway in said wall, said door having associated therewith a duct which aligns with said flue when the door is closed to 30 form a continuous passage, the combination of a member resting on the upper surface of said drip pan and arranged to divert liquid to the flue on either side of the doorway when the door is open, said member being mounted upon a pivoted arm so that closing said door rotates said arm and lifts said member from the drip pan to permit flow of liquid through said duct. 35

4. In a refrigerator car having spaced apart insulated walls, an insulated roof extending therebetween, a drip pan sloping downwardly toward one of said walls and spaced below said roof to provide a refrigerant compartment there-

between, a flue associated with said wall and arranged to transmit air and liquid from said compartment to the lower part of the car, a doorway through said wall and said flue and a door adapted to close the doorway in said wall, said door having associated therewith a duct which aligns with said flue when the door is closed to form a continuous passage, the combination of a member on the upper surface of said drip pan arranged to divert liquid to the flue on either side of the doorway when the door is open, said member being mounted upon a pivoted arm so that closing said door rotates said arm and lifts said member from the drip pan to permit flow of liquid through said duct, and a spring adapted to yieldingly hold said member against said drip pan when the door is open. 60

5. In a refrigerator car having spaced apart insulated walls, an insulated roof extending therebetween, a drip pan sloping downwardly toward one of said walls and spaced below said roof to provide a refrigerant compartment there- 70

between, a flue associated with said wall and arranged to transmit air and liquid from said compartment to the lower part of the car, a doorway through said wall and said flue and a door 5 adapted to close the doorway in said wall, said door having associated therewith a duct which aligns with said flue when the door is closed to form a continuous passage, the combination of a member extending beyond the sides of said doorway on the upper surface of said drip pan to direct liquid to the flues on both sides of the door- 10

way when the door is open, and means by which said member is spaced from said drip pan when the door is closed to permit flow of liquid through said duct.

6. A structure as defined in claim 2 wherein an edge of said member slopes downwardly toward said flue for draining of liquid. 5

7. A structure as defined in claim 2 wherein said member is provided with a pliable surface for watertight contact with said drip pan. 10
